UNITED STATES PATENT OFFICE

CLIFFORD C. CARSON, OF CHICAGO, ILLINOIS

DOWN-DRAFT UNIT HEATER

Application filed May 31, 1930. Serial No. 458,301.

This invention relates to unit heaters of the suspension type and, among other objects, aims to provide an improved down-draft heater having novel means for discharging a curtain of air around and above the heated air so as to confine the heated air for a substantial period to circulate in the space to be heated or below the breathing line.

10 This application involves certain important improvements on the apparatus disclosed in my co-pending application, Ser. No. 308,681, filed September 27, 1928.

15 Other aims and advantages of the invention will appear in the specification when considered in connection with the accompanying drawings, wherein:

20 Fig. 1 is a side elevation of a direct-fired, suspension type heater embodying the invention;

Fig. 2 is a bottom plan view of the heater shown in Fig. 1;

Fig. 3 is a central sectional view; and

25 Fig. 4 is a section taken on the line 4-4 of Fig. 3.

Referring particularly to the drawings, the heater is shown as having provision to be suspended from roof joists or the like in a building or large room and is adapted to be arranged at any convenient height above the floor, the idea being to conserve the floor space and to discharge the heated air downwardly so as to break up the cold air film adjacent to the floor and cause the heated 35 air to circulate in the space to be heated. In this example, the heater is of the direct fired type and is adapted to utilize any suitable fluid fuel, either liquid or gaseous. However, it will be understood that the invention is not limited to direct fired heater units.

Referring to Figs. 1 and 3, the heater is there shown as having sheet metal casing walls 10 secured to box headers 11 and 12 at the opposite ends to which groups of return fire tubes 13 are connected. The box header 12 is here shown as having a fire box portion 14 in the lower part and the fuel is supplied to the fire box through a series 45 of nozzles 15. The arrangement is such that

either liquid or gaseous fuel may be utilized without making any alterations. The products of combustion pass through the lower group of tubes shown in Figs. 3 and 4 to the return smoke or box header 11; thence 55 through the upper group of tubes into the upper portion of the fire box header 12 above a division plate or partition 16 and out through a suitable stack 17. In this instance, the tubes 13 are welded or otherwise secured in suitable openings in tube sheets 18 and cast or sheet metal boxes are bolted or otherwise suitably secured to the plates. However, the box headers may have hand hole openings to afford access to the 60 ends of the fire tubes.

The upper end of the casing defined by the side walls and smoke boxes or headers, is open to admit air to circulate through the casing about the fire tubes which are conveniently arranged in staggered relation.

To the lower inside edges of the fire tube sheets 18 and the side walls 10 of the casing is connected a sheet metal conduit 19 having a reduced lower end through which the air 70 is adapted to be discharged downwardly after being heated by the fire tubes. Below the lower end of this conduit is arranged a fan 20 of the impeller type which is driven by a motor 21 supported on suitable arms 75 or brackets 22. The arms are conveniently made of tubular stock and are likewise connected to the box header and the side walls of the heater casing. In this instance, the upper ends of the arms and the outlet conduit 19 are secured to the lower portion of the heater by means of bolts passing through suitable flanges in the box headers 11 and 12 and also through the tube sheets 18. The same set of bolts or rivets, as the case may 80 be, are here used to secure both members to the casing. The arms 22 extend radially and horizontally from the supporting collar for the motor 21 and on these arms is secured a bell-shaped sheet metal conduit or 85 outlet nozzle 23 having radial openings through which the arms are inserted before being connected to the motor supporting collar. The arrangement is such that the heated air induced by the fan 20 is dis-

85

100

charged downwardly in a substantially frusto-conical stream through the bell-shaped nozzle. To protect the motor from the influence of the heat, there is shown a deflector shield 24 supported upon and suitably secured to the upper edges of the arms or bracket members 22 adjacent to the motor casing.

In Fig. 3, the blades of the fan are shown as extending beyond the circular edge of the lower end of the conduit 19. An annular sheet metal wall 25 is shown as being secured to the arms 22 and spaced from the outer walls of the conduit 19 and the nozzle 23. The lower end of this sheet metal member is flared outwardly. The arrangement is such that the extended ends of the blades of the fan 20 discharge an umbrella-shaped curtain of air through the annular passage 26 between the wall 25 and the bell-shaped nozzle 23, the flared lower ends of the nozzle and the wall being shaped somewhat like a Venturi nozzle. This curtain of air is sucked in through the annular space around the upper portion of the conduit 19 and between the reduced lower end portion and a horizontal annular flange 27 on the sheet metal wall 25. Since the peripheral speed of the outer ends of the fan blades is much greater than that of the inner end portions, and the annular passage 26 for the air curtain is of less cross sectional area than the outlet passage for the heated air, the velocity of the curtain of air is considerably greater than the velocity of the discharging heated air.

It will be observed that the curtain of air is discharged at an angle to the vertical. This angle is determined largely by the height at which the heater is suspended and the operating conditions. The idea is to have the curtain envelop the stream of heated air and flatten out horizontally at or near the breathing line. The heated air is confined thereby to circulate below the breathing line. It is contemplated that the angularity of the discharging nozzle may be between 15° and 45° to the vertical. The shape of the flared or bell-shaped nozzle 23 and of the sheet metal housing or wall 25 may be made to suit the conditions under which the heater is to work.

From the foregoing description, it will be observed that the intake air for the heater is admitted through the upper end of the casing and heat is initially absorbed by it from the upper group of fire tubes. These fire tubes are somewhat cooler than are the tubes of the lower group. As the air passes around the tubes of the lower group, which are hottest, it absorbs a final increment of heat. By this arrangement of tubes, the temperature difference between the air and the heating surfaces is maintained more nearly constant,

thus providing a very high heating efficiency. Moreover, the intake air coming from the upper portion of the room or building is somewhat warmer than is the air adjacent to the floor and this further economizes with fuel. Furthermore, the umbrella curtain of air is somewhat warmer than it would be if taken from a point nearer the floor. Hence, the temperature difference between the curtain and the discharging heated air is not very great. Since the heater is of the down-draft type, air will circulate through it even when the fan is not running and thereby prevent the fire tubes from being burned out. The discharge nozzle and the casing will act as a stack for the air and a natural draft will be set up. Of course, it is contemplated that any convenient automatic controlling apparatus may be employed in connection with the fuel burners and the motor for driving the fan.

While the novel apparatus for confining a vertical stream of heated air by means of an umbrella-shaped or frusto-conical curtain of high velocity air is shown as being connected to the lower end of a direct fired heater, it is to be understood that it may be used in combination with the ordinary steam or hot water units now commonly employed. The direct fired unit is well adapted for use in sections of the country where natural and/or artificial gas are available at low rates. Moreover, such heaters can be employed advantageously where crude oil is used as fuel.

Obviously, the present invention is not restricted to the particular embodiment thereof herein shown and described. Moreover, it is not indispensable that all the features of the invention be used conjointly, since they may be employed advantageously in various combinations and sub-combinations.

What is claimed is:

1. A down-draft unit heater comprising air heating means; a discharge conduit connected to discharge heated air downwardly; and means to discharge an enveloping curtain of air around and above the discharging heated air.
2. A down-draft unit heater comprising air heating means; a discharge conduit connected to discharge heated air downwardly; and means to discharge a thin, frusto-conical curtain of air around and above the discharging heated air.
3. A suspended unit heater comprising a heat exchanger; a vertical discharge nozzle connected to discharge the heated air downwardly and means to discharge a frusto-conical curtain of air at a relatively high velocity around the discharging heated air.
4. A unit heater of the character described comprising, in combination, direct fired heat-

ing means; a casing for the heating means; a fan supported by the heater and connected to discharge heated air downwardly from the casing; and means for directing an umbrella-shaped curtain of air downwardly and at an angle to the vertical around the discharging heated air.

5. In a unit heater of the character described, a discharge nozzle for heated air arranged to direct the air downwardly; a fan for blowing the air through said nozzle; an annular conduit surrounding said discharge nozzle; and a single fan arranged to discharge heated air through said nozzle and relatively cold air through said conduit at a greater velocity than the heated air so as to confine the heated air to circulate in the lower portion of the space to be heated until it has given up a substantial portion 20 of its heat.

6. A unit heater of the character described comprising, in combination, a horizontal return fire tube heater unit having an associated fire box; a casing surrounding the 25 heater; a vertical discharge conduit connected to the lower portion of the heater; a substantially bell-shaped nozzle for the heated air; a fan between the conduit and said nozzle; an annular passage surrounding 30 said nozzle; and means to discharge an umbrella-shaped curtain of air through said annular conduit around the discharging heated air.

7. A unit heater of the character described comprising, in combination, a horizontal fire tube heater unit having an associated fire box; an air discharge conduit connected to the lower end of the heater unit; a propeller fan below the discharge 40 conduit; a bell-shaped nozzle supported below the fan; a sheet metal wall spaced from the bell-shaped nozzle and providing an annular conduit; the blades of said fan extending into said annular conduit and arranged to discharge air therethrough around the discharging heated air so as to confine the heated air to circulate in the space below the breathing line until it has given up a substantial portion of its heat.

50 8. A unit heater of the character described comprising, in combination, a horizontal direct fired, fire tube heater unit having a conduit connected to its lower side and arranged to discharge air downwardly therefrom; a fan arranged to discharge air through said conduit; a sheet metal wall surrounding said conduit and providing an annular passage for relatively cool air around the discharge end of said conduit; 60 and means to create a high velocity stream of air through said annular passage so as to discharge around the discharging heated air and confine it to circulate in the lower portion of the space to be heated until it has given up a substantial portion of its heat.

9. In a unit heater of the character described, a down-draft heater element; a plurality of supporting arms connected to said heater element; a motor supported by said arms; a fan driven by said motor; a vertical discharge nozzle below said fan; and means associated with said fan to discharge an umbrella-shaped curtain of relatively cold air around the heated air discharged by said fan so as to confine the heated air to circulate in the lower portion of the space to be heated until it has given up a substantial portion of its heat.

10. In a unit heater of the character described, a down-draft heater element; a vertical discharge conduit connected to the heater; a fan below the heater element; a fan motor supported in the conduit below the fan; and a shield in the conduit between the fan and the motor to protect the 85 motor from the influence of the discharging heated air.

In testimony, that I claim the foregoing as my own, I have hereto affixed my signature.

CLIFFORD C. CARSON.
